UNITED STATES PATENT OFFICE.

WILLIAM ELLIS, JR., OF NORTH LAWRENCE, KANSAS.

ROAD-SCRAPER.

SPECIFICATION forming part of Letters Patent No. 301,051, dated June 24, 1884.

Application filed February 14, 1884. (No model.)

To all whom it may concern:

Be it known that I, WILLIAM ELLIS, Jr., a citizen of the United States of America, residing at North Lawrence, in the county of Douglas and State of Kansas, have invented 5 certain new and useful Improvements in Road-Scrapers; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

15 My invention relates to that class of road-scrapers which are double-ended and constructed to revolve for the purpose of dumping its contents; and it consists in the arrangement and construction of the various parts 20 thereof, so that the effective operation of the device is readily secured.

In the accompanying drawings, Figure 1 is 25 a perspective view of my improved road-scraper. Fig. 2 is a perspective view of the operating-frame, the end of the lower lever being slotted, as indicated by dotted lines, Figs. 1 and 2, to permit the pivot-bolt to play 30 therein when the said ends are moved rearward. Fig. 3 is an inverted plan of a part of the operating-frame. Fig. 4 is an enlarged detail view.

The improvements described and set forth in the present application have relation to the structure covered in my Patent No. 273,830, 35 issued March 13, 1883, to which patent a reference may be had for a full understanding of the general principles of the device.

A is the scraper, formed and arranged as shown in said patent. The sides of said scraper 40 are each provided with a journal, *a*, upon which is mounted a disk, *b*, secured to the side of the scraper, so as to revolve therewith. Each of these rollers *b* is cut away at its periphery to 45 form shoulders *c d*, each being half the width of the periphery and reversed, as shown in Fig. 4.

A metallic case, *B*, is secured to the forward end of each of the handles *C*, and is provided with a perforated extension, *e*, at its front, 50 adapted to engage one of the journals *a* of the scraper. Through each case *B* play two bolts,

f f', one of which bolts, *f*, is connected at its rear end to the perforated end of a lever, *g*, centrally pivoted on the cross-bar *D*, connecting the handles. The levers *g* are pivotally 55 connected together at their inner ends. A curved hand-lever, *h*, is pivoted to the end of each of the handles *C*, and is connected at its forward end to the outer end of the adjacent lever *g* by a link, *i*. A tension-spring, *E*, is 60 secured on the bottom of the cross-bar *D*, as shown in Fig. 3, and has its extremities extended to engage the outer ends of the levers *g*, as shown in Fig. 2. This tension-spring tends to maintain the outer ends of the levers 65 *g* in the position illustrated. A small hand-lever, *F*, is pivoted on the cross-bar *D* at the rear of the central connection of the levers *g*, and said hand-lever carries at one end a roller, *j*, journaled loosely on its end, and adapted, 70 when said hand-lever is moved in a position parallel with the handles *C*, to bear against the inner connected ends of the levers *g* and force them forward, thus throwing the outer ends rearward. Two plates, *G*, of spring metal, 75 are secured at their upper ends, one to the inner side of each of the handles *C*, so as to depend therefrom, the ends *k* of said plates being bent up, as shown in Fig. 2.

The draft-bail *H* is bent in toward the sides 80 of the scraper *A*, so as to form extensions *l* of said draft-bail. Brackets *I*, provided with blades *m*, are adapted to be secured to the sides of the scraper *A*, as shown in Fig. 1. The bolts *f f'*, arranged side by side, are adapt- 85 ed to engage the shoulders *c d* of the disk, which shoulders being reversed will cause the bolt *f* to be above the shoulder *c*, while the bolt *f'* is below the shoulder *d*. The bolt *f'* is spring-seated in the case *B*, so as to yield, 90 but may be otherwise connected to be retracted within said case when necessary.

By depressing either of the handles *h* the outer ends of the levers *g* are drawn backward against the spring-tension, thus withdrawing 95 the bolts *f* and permitting the weight of the load in the scraper to dump and revolve the scraper, the position of the bolt *f'* with regard to the shoulder *d* preventing any reverse movement of the scraper. When the scraper 100 revolves forward, the disk *b* turns therewith and forces the bolt *f'* back into the case until

the terminus of said shoulder is reached, at which point the bolt is forced beneath said shoulder to occupy the position first described.

By making the case B and its extensions *e* 5 in one piece the parts may be readily cast and great durability secured, and the entrance of dirt to prevent the working of the bolt prevented.

By the arrangement of devices on the cross-bar D both bolts *f* may be operated from either side of the machine, or by manipulating the lever F the bolts may be withdrawn and retained in their disengaged position.

The depending plates G not only serve as 15 rests for the scraper, but their spring ends permit the upward movement of the scraper in contact with said ends, but oppose any downward movement of said scraper.

Should the frame composed of the handles 20 C and their connections be thrown forward accidentally or otherwise, the said handles will come in contact with the extensions *l* of the draft-bail H.

The cutter-brackets I insure the regular 25 trimming of the sides of the space in which the scraper travels.

I claim—

1. The combination, in a road-scraper, of a 30 scraper proper pivoted in a suitable frame by journals, and provided with a disk having reverse shoulders located in parallel peripheral planes, as described, and bolts arranged and operating to respectively prevent the forward and rearward rotation of said disk, substantially as set forth.

2. The combination, in a road-scraper, of a 35 scraper proper pivoted in a suitable frame by journals, and provided with a disk having reverse shoulders, and two bolts arranged on the frame supporting the scraper proper, one operated by hand-lever connections secured on the frame and the other automatically yielding, substantially as described.

3. The combination, in a road-scraper, of a 40 scraper proper having journals located at its sides, a notched disk secured to said scraper, a case secured on one side at the forward part

of the supporting frame, and provided with an extension perforated to receive one of the journals, a bolt playing through said case, and 50 devices for operating the same, substantially as described.

4. The combination, in a road-scraper pivoted in a suitable frame by journals, and provided with a disk having reverse shoulders located in parallel peripheral planes, as described, of bolts arranged to respectively prevent the forward and rearward rotation of said disk, and handles pivoted at each side of the upper end of the frame and connected with 55 said bolt devices, substantially as set forth.

5. The combination, in a road-scraper, of a 60 scraper proper pivoted in a frame, bolt devices for locking it in its pivoted position, mechanism for disengaging said bolt devices, and means for locking said devices in their disengaged position, substantially as set forth.

6. The combination, in a road-scraper pivoted in a suitable frame by journals, and provided with cutter-brackets bolted to the sides 70 of the same, of a disk having reverse shoulders located in parallel peripheral planes, as described, and bolts arranged to respectively prevent the forward and rearward rotation of said disk, substantially as set forth.

7. The combination, in a road-scraper, of a 75 suitable frame provided with depending plates G, bent and arranged for the purpose set forth, a scraper proper pivoted in said frame, and provided with a disk having reverse shoulders located in parallel peripheral planes, as described, and bolts arranged to respectively prevent the forward and rearward rotation of said disk, substantially as set forth.

8. The combination, with a road-scraper constructed and operating substantially as herein described, of a draft-bail provided with extensions *l*, for the purpose specified.

In testimony whereof I affix my signature in presence of two witnesses.

WILLIAM ELLIS, JR.
